UNITED STATES PATENT OFFICE.

ARTHUR M. CORNELL, OF CHICAGO, ILLINOIS.

GUARD-RAIL.

1,337,544.

Specification of Letters Patent. Patented Apr. 20, 1920.

Application filed April 23, 1918. Serial No. 230,213.

To all whom it may concern:

Be it known that I, ARTHUR M. CORNELL, a citizen of the United States, residing at Chicago, in the county of Cook and State of Illinois, have invented certain new and useful Improvements in Guard-Rails, of which the following is a description.

My invention belongs to that general class of devices known as guard rails to be used in accordance with the general railway practice, opposite frog points and at such other places as desired adjacent the track rail for the purpose of guiding or deflecting the wheel flanges to avoid derailment. The invention has among its objects the production of a device of the kind described that is simple, convenient, durable, efficient and satisfactory for use wherever found applicable. More particularly it has as an object the production of a universal one piece guard rail which will transmit all strains back to the traffic rail, which may be adjusted and secured in place without the use of bolts, screws, coppers, or the like, and is applicable for use with different sized traffic rails, no filled blocks being necessary to maintain the desired flange-way. It has particularly as a further object the production of a device which will have a maximum of life, since it may be adjusted for wear, which may be applied to or removed from the track without in any way disturbing the running or traffic rail, regardless of whether the running rail is tie plated or not, it being applicable to the track without the use of special tools. The device is so constructed as to eliminate all unnecessary material and reduce the weight and cost, and in addition the same will not pack with snow, thereby impairing the efficiency of the same in use or making it unsafe. Many other objects and advantages of the construction herein shown and described will be obvious to those skilled in the art from the disclosures herein given.

To this end, my invention consists in the novel construction, arrangement and combination of parts herein shown and described and more particularly pointed out in the claims.

In the drawings, wherein like reference characters indicate like or corresponding parts,

Figure 1 is a view in elevation of a track with guard rails applied thereto; 55

Fig. 2 is a view in plan of the preferred form of the device applied to the traffic rail;

Fig. 3 is a plan view of a wedge engaging member; 60

Fig. 4 is a view in elevation of the rail;

Fig. 5 is a sectional view taken substantially on line 5—5 of Fig. 2; and

Fig. 6 is a perspective view of one of the wedge members. 65

Referring to the drawings, 1 represents a traffic rail provided with the usual base 2 and connecting web 3, the same being supported on the ties 4 and secured in place by the spikes 5 or the equivalent. The rail 70 may be tie plated or not as desired, it being immaterial as to how the traffic rail is secured to the ties or how the ties are constructed.

Referring particularly to Fig. 5, the guard 75 rail consists of a rail part 6 preferably flanged as at 7, constituting a rail of inverted L-shape connected to a base plate 8 by the ribs 9. The number of ribs and their distance apart, as well as the proportions of the various parts, obviously depends upon the particular use for which the guard rail is intended. The ends of the rail are preferably formed at an angle as at 10—10 (see Fig. 2) on the inner side. I 85 also prefer to provide the base 8 with holes 11, through which spikes or the like may be driven into the ties. A sufficient number of holes or slots 11 are provided in the base plate so that all desired ties may be 90 secured to by two spikes if desired, without requiring moving the tie. As a matter of fact, the holes 11 and spikes are not essential to the invention, but the same serve as an additional factor of safety and prevent creeping of the guard rail. The plate 8 is provided with the desired number of extending parts 12, each of which passes under the rail, and is thence turned back toward the guard rail as at 13, the same being strengthened by the fin or rib 14. At the end of 13 is provided a part 15 having an inner face 16 at an angle, which face is formed with one or more lugs 17, or in 95 an equivalent manner. Arranged to co-operate with the face 16 and the lugs is a suit-

100
105

ably formed part or member 18 having an inclined face 19, and provided with the desired number of recesses 20 of a size to receive the lugs 17, and with lugs engaging 5 between the lugs 17. It will be noted by referring to Fig. 2, in which the guard rail is shown with two parts extending under the rail, that the faces are inclined in opposite directions. The flange part 7 carries the foot guard part 21 adjacent each 10 end, as most clearly shown in Figs. 2 and 5.

In securing the guard rail in place it is positioned substantially as shown in the drawings, with the member 18 adjusted as 15 desired. The particular position or assembly of the member determines the distance the guard rail is from the tread 1 of the traffic rail. By spiking the guard rail to the ties the same is prevented from creeping 20 or becoming displaced. However, the foot guard parts 21 and the member 18 at each end will normally prevent transverse displacement of the rail, so that it will always be maintained in a safe position. It will be 25 readily understood that the device may be applied or removed without in any way displacing the traffic rail by applying or removing the members 18 and the spikes, provided the spikes are used.

30 The construction is such that the guard rail may be standardized and applied to various sections of rail, only the members 18 being specially made to fit, it occasionally being necessary to vary the size of the members 18 for different rails. The strain of 35 rolling stock engaging the guard rail passes from the guard rail through parts 12 and the members 18 to the traffic rail, and this is held in place by the weight of the rolling 40 stock which produced the initial strain, as well as by the fastenings securing the same to the ties. Not only do the ribs 9 reduce the material used, but in addition snow will 45 not pack in the flange-way. It will be noted that the guard rail takes the strain and transmitting it through suitably designed members puts it back on the traffic rail, thus eliminating wear and breaking strain. The guard rail described is so designed as to 50 be applicable to different heights of rails, thus making it interchangeable and reducing the necessary repair material which must be carried by each section gang, as well as facilitating prompt repairs. As was before 55 mentioned, the open web reduces weight and cost, and the design of the rail is such that it may be adjusted when worn, thus affording maximum life to the rail.

Having thus described my invention, it is 60 obvious that various immaterial modifications may be made in the same without departing from the spirit of my invention, hence I do not wish to be understood as limiting myself to the exact form, con-

struction, arrangement and combination of 65 parts herein shown and described or uses mentioned.

What I claim as new and desire to secure by Letters Patent is:—

1. A track guard rail structure comprising 70 the combination of a base plate provided with a plurality of upwardly extending and inclined posts between its ends, and having regularly spaced holes therethrough between the posts, a rail portion carried at the upper 75 ends of said posts with the side face of the rail portion extending beyond the edge of the base plate, the ends of said rail portion turned back over the base plate and provided with a foot guard at each end, said 80 base plate provided with extending parts of suitable length to project under the base portion of the track rail adjacent the top face of the said extending parts below the lower face of the base plate, whereby the 85 same may underlie the track rail, the free end of each extending part extending upwardly and thence back, and each provided with a suitably formed face, and a coöperating member for each extending part of a 90 size to engage said face and the web and base flange at the outer side of the track rail.

2. In a guard device of the kind described 95 for track rails and in combination, a guard structure comprising a base plate provided with a plurality of regularly spaced holes therethrough, and having upwardly extending and inclined posts regularly spaced from 100 end to end of the base plate, a rail portion comprising an inverted L-shaped rail portion carried by said posts with the inner face of the rail portion extending above and beyond the inner edge of the base plate, said 105 base plate provided with means for engaging the adjacent track rail at the outer face of the web thereof on the opposite side thereof comprising extending parts formed integrally with the plate on the under side thereof, and of a length to extend under and 110 beyond the track rail base flange, the free ends of said parts turned upwardly and back toward the outer face of the track rail web but spaced therefrom, a suitably shaped part 115 for each upturned end, each formed to engage the face on said ends and the web of the track rail between the head and base flange thereof, said part adjustable relative to said extending part, whereby the distance 120 between the rail portion and the track rail may be varied as desired.

In testimony whereof I have hereunto signed my name in the presence of two subscribing witnesses.

ARTHUR M. CORNELL.
